UNITED STATES PATENT OFFICE.

BÖRRE H. BÖRRESON, OF ST. PAUL, MINNESOTA.

LICENSE TAG FOR MOTOR VEHICLES.

Application filed November 12, 1921. Serial No. 514,615.

To all whom it may concern:

Be it known that I, BÖRRE H. BÖRRESON, a citizen of the United States, resident of St. Paul, county of Ramsey, State of Minnesota, 5 have invented certain new and useful Improvements in License Tags for Motor Vehicles, of which the following is a specification.

The object of my invention is to provide 10 a tag made in such a way that the license number for both the rear and the front of the car, the certificate of registration, the State and county files and the owner's receipt, and a blank for the sale and purchase certificate, 15 may all be printed on one sheet and folded so that when the original certificate of registration is made out, duplicates thereof will appear on the State and county files and the owner's receipt. Duplicates also will be 20 made of the sale and purchase certificate when it becomes desirable to fill out the blanks for that purpose.

The invention consists generally in various constructions and combinations, all as hereinafter described and particularly pointed out in the claims.

In the accompanying drawings forming part of this specification.

Figure 1 is a view of the unfolded sheet, 30 showing the license numbers for the front and rear and the blanks that will appear on one side of the sheet.

Figure 2 is a similar view of the back or rear side of the unfolded sheet, showing the 35 duplicates of the certificate of registration for the State file and the owner's receipt, and also showing on the reverse side a form of sales certificate, which also becomes application for a new number,

40 Figure 3 is a face view of the tag for the front of the car, showing the certificate of registration at one end of the tag,

Figure 4 is a detail view of one end of the 45 certificate of registration, showing the manner of placing the original license number thereon, the transfer number in case of sale of the car, and previous license numbers.

In the drawing, 2 represents the tag at one 50 end of the sheet, designated for the license number at the rear of the car, and 3 is the section of the tag for the license number at the front of the car. These numbers will correspond and precede the license number I provide figures indicating the arbitrary 55 number of the county in the State in which the certificate of registration is issued.

For instance, in this particular case, "53" is used as the number of a certain county in the State of Iowa. The license number is shown as 7239, with a small design separating the license number from the county number. Above the license number appears the name of the State, with the year the certificate is issued, and following the figures indicating the year, I provide letters of the alphabet, 60 which indicate the first figure of the license, thereby economizing space on the tag. For instance, in the illustration, the letter "B" is shown, thus indicating that the first figure of the license number is "2," the whole number 70 being 27,239. If the letter "A" is shown, then the number will be 17,239. If the letter "C", the number would be 37,239, and so on through the alphabet.

The section of the sheet for the official 75 license tag is provided at one end with a blank space 4 to be filled in for the certificate of registration. In this space a description of the person to whom the license is issued is written. This description includes 80 the name, age, weight, of the person, color of hair and eyes, and other descriptive matter usually embodied in certificates of this kind. The original of this certificate becomes a permanent part of the license tag 85 at the front of the machine, and being mounted in a suitable frame, is plainly visible and can be inspected by any one.

Adjoining this certificate of registration is a panel 5 folded along the transverse line 6 90 and having a duplicate of the certificate of registration on its reverse side so that when the panels are folded, the duplicate of the registration certificate will be positioned to take a carbon impression or carbon of the 95 original. The next panel 7 adjoining the panel 5 and folded also on a transverse line 6^a has a blank on its obverse face so that a carbon impression or copy of the original will be made when the original is filled out, 100 and adjoining this panel 7 is an end panel 8 folded along a transverse line 6^b having a blank for the sales certificate and on its reverse face a copy 8^a of the original certificate of registration. This certificate is 105 kept by the owner and may be used as a means of identification or for establishing the ownership of the car.

By making out the sheet in this way one entry of the description in the original certificate will reproduce one for the file of the Secretary of State, another for the file of

the county, and a third for the owner's receipt, and all of these certificates will, of course, correspond.

As shown in Figure 2, the reverse side of 5 the sheet at one end of the front license tag is provided with a blank 9 for a carbon copy of the certificate of registration for the State file. Adjoining this carbon copy, also on the reverse side of the sheet, is a sales certificate 10 on which a carbon is made from the original of the panel 5 on the face of the sheet. Adjoining this carbon copy of the sales certificate is a blank for a third copy 8^a of the certificate of registration, which 15 constitutes the owner's receipt. On the other side of this owner's receipt certificate is a third copy of the certificate of sale.

In making out the blanks on the sheet, 3 carbons are made of the certificate of registration from the original, which forms a permanent part of the front license tag on 20 the car. One carbon is filed with the Secretary of State, another with the county issuing the certificate, and a third is retained by 25 the owner. In case of a sale of the car, two carbons of the certificate of sale are made from the original. When this work is completed all the sections properly filled out 30 will be detached from the original certificate of registration, which, as stated, forms a permanent part of the tag and the others being carbons, must of course be identical. In this way a considerable saving is effected in 35 the matter of filling out and filing blanks and exact copies or reproductions of the originals are insured, and provide complete records of transactions between the various departments.

In Figure 4 I have shown the preferred 40 form of the certificate of registration, having little squares at the corners in one of which appears numerals corresponding to those on the license tags, also the transfer number and date. The other corner of the 45 certificate has blanks for the previous license numbers. In this way the ownership of a car can be traced back through the different owners and a complete record of the sales transfers obtained. Corresponding 50 numbers will, of course, appear in the carbon copies of the certificates of registration. The present license number would be printed on the blanks when they are prepared, but the other numbers and years of issue 55 will be filled in by the county official when the new numbers, through sale or transfer, are issued. Perforations are provided in the sheet between the tags and cards, so that they may be easily separated for filing purposes. The sheet will be folded along these 60 perforated lines so that the blanks can be easily filled in on the typewriter and then the cards are separated and distributed to the different departments, the general purpose of the whole card being to prevent 65

fraudulent duplication and the sale of a stolen car. The license number on the cards or tags will be the same throughout the sheet, in the one shown, the number indicating the arbitrary number of the county and 70 the license number, and the records in the different departments will all correspond. By making this sheet in such form that carbon copies may be made of the original entries, it is evident that the chances of error 75 are practically eliminated, each department will have a complete, accurate record of the license-card, and all transactions relating to the machine on which the card is used.

A Federal tax collected through State and 80 county officials may be indicated on the certificate of registration, which will also provide a record of receipts of payments of the tax through such officials; thus National, 85 State and county records may be maintained through the medium of the original and duplicate certificates.

I claim as my invention:

1. A flexible sheet comprising panels arranged end to end and adapted to be separated, one having a license number thereon for the rear of the car, the other panel having a corresponding license number for the front of the car and also having at one end a permanently attached certificate of 90 registration.

2. A flexible sheet comprising panels arranged end to end and adapted to be separated, one having a license number thereon for the rear of the car, the other panel having a corresponding license number for the front of the car and also having at one end a permanently attached certificate of registration, said sheet also having a series of blank 100 sections adapted to be folded one upon the other for making reproductions of said certificate of registration, for the purpose specified.

3. A flexible sheet having a space for a car license number and a permanently attached blank section for the certificate of registration, said sheet also having sections adapted to be folded one upon the other, said sections having upon their opposite faces blanks for making reproductions of 110 the original certificate of registration, one of said sections being designated for a sales certificate and other sections having blanks 115 for making reproductions of said sales certificate.

4. A license tag comprising a flexible sheet, elongated in form, having a panel at one end adapted to be detached and bearing the number of the license tag, a second panel also bearing the number of the license tag, a blank for the certificate of registration being provided at one end of said second panel and said sheet being folded transversely at intervals to form a series of panels adjoining the certificate of registration 125 130

panel, said series of panels having blanks alternately arranged, one group corresponding to the certificate of registration blank and the other group forming sale and license certificates, said panels being so folded that when the original certificate is filled out, a reproduction may be made on all the other certificates of the same group.

5. A flexible sheet comprising a panel having a license number thereon for one end of the car and also having a permanently attached certificate of registration.

6. A flexible sheet comprising a panel having a license number thereon for one end of the car and also having a permanently attached certificate of registration, said sheet also having a series of blank sections adapted to be folded one upon the other for making reproductions of said certificate of registration, for the purpose specified. 15

In witness whereof, I have hereunto set my hand this 4th day of November 1921.

BÖRRE H. BÖRRESON.
